ELEVATOR DOOR LOCK

August W. Bleyle, Palo Alto, Calif.

Application May 2, 1944, Serial No. 533,776

10 Claims. (Cl. 200—55)

1

This invention relates to elevator door locks and more particularly to combined mechanical latches and circuit control switches for electric elevators.

Among the objects of the invention is the provision of an automatic latch that is proof against tampering.

Another object is to so construct the latch that it is equally applicable to horizontally and vertically guided, and radially swinging doors, by a simple rearrangement of the cam trip.

A further object is the provision of a positively controlled gravitating catch, free from spring actuated pivotal members.

A further object is the combining of an automatic circuit making and breaking switch with and controlled by the mechanical operation of the door and latch.

Other objects and advantages will appear as the description proceeds.

In the specification and drawings the invention is disclosed in its preferred form. But it is to be understood that it is not limited to this form, because it may be embodied in modifications within the spirit of the invention as defined in the claims following the description.

In the one sheet of drawings:

Fig. 1 is a side elevation of latch and switch assembly, with the cover partially removed, and the cam trip in the plane of the door and the latch in the closed condition.

Fig. 2 is a top view of the assembly indicating in interrupted lines the selective positions of the latch tripping mechanism.

Fig. 3 is a detail in end elevation of the catch tripping cam assembly, showing the cam block in vertical section.

In detail the structure shown in Fig. 1, comprises the encircling case 1, preferably of cast metal screwed to the door frame X and having the side covers 2, 3. These covers are attached to the opposite sides of the frame by screws, such as 4, 5, in alignment on the opposite sides of the frame, respectively. The front wall 6 of the frame is recessed vertically to guide the flat catch 7 freely slidable therein. This catch is enclosed by the edge wall 8 of the case 1, having the catch opening 9, and the switch opening 10 therethrough.

The cam trip comprises the shaft 11 pivoted in the hollow block 12, fixed to the internal bracket 13 on the frame, by the screw 14. The arm 15 is adjustably fixed on the shaft by the clamp screw 16. The dielectric roller 17 is adjusted in the path of the usual magnetically re-

2

tractable cam Y indicated in dotted lines and mounted on the elevator cage. This cam automatically moves outward against the roller 17 as the cage stops at the floor level.

The double acting latch cam 18, see Fig. 3, is fixed on the shaft 11 within the block 12. The cam yoke 19 clears the shaft 11 and rests upon the cam lugs 18, 18'. This yoke has the stem 20 protruding through and guided in the top of the block 12. The opposed lugs of this cam are set about in line with the axis of the shaft 11 to give the maximum lift of the yoke 19, with minimal rotation of the shaft.

The catch actuating the weighted pressure lever 21 is pivoted to the frame 1 at 22 and rests upon the pointed head of the stem 20. The front end of this lever has the lug 21' engaging within a cross slot in the top of the catch 7. When the arm 15 is tripped by the cam Y on the cage it rotates the shaft 11 and cam 18, causing it to lift the lever 21 and the catch 7. This releases the head of the tapered catch 23 fixed on the bracket plate 23', that is mounted on the front edge of the door Z.

The switch for opening and closing the circuit controlling the elevator cage, consists of the dielectric base 24 fixed to the frame 1. The binding posts 25, 26, in the operating circuit, pass through the base 24 and have the contacts 25', 27 thereon. The yielding blade 28 is yieldingly mounted on the insulator 29 fixed to the catch plate 7. A wiping blade 30 bears against the contact 27. These blades 28, 30 contact the bus bar 31, mounted upon the insulating block 32 on the door Z. This switch closes the circuit when the door is closed and opens it when the door is opened.

The width of the block 12 is equal to the depth of the case 1, permitting it to be readjusted to function in the various positions illustrated in Fig. 2. The cover 2 has a hole opposite the axis of the shaft 11. When covers 1, 2, are reversed to the opposite sides of the case 1, the shaft 11 can be extended as at B. Taken with Figs. 1, 2, 45 this gives three possible positions, A, B, C of the shaft 11, relative to the plane of the case, on either side of the door frame X. For swing doors the plane of the case is set perpendicular to the plane of the door frame, with the shaft projecting laterally as at A. For vertically sliding doors, as for large freight elevators, the case 1 is fixed to the top of the door frame, with the shaft 11 projecting as at C into the path of the retractable cam Y on the elevator cage. In this instance it will be necessary to substitute an expensive spring

21 x between the adjacent end of the case and the lever **21** as a substitute for the weight of the lever **21**, to normally force the latch **7** into locking position. The pressure of the spring being overcome by the cam action of the inclined nose **23** of the latch **23** when the door closes.

It is important to coordinate the latch, catch and switch so that the operating circuit is open until the catch **7** drops behind the latch **23**, before the bus bar **31** contacts the blade **30**.

This invention operates substantially as follows: Referring to Fig. 1, when the elevator cage reaches the selected door level and is stopped, by opening the circuit by the usual operator's manual control or automatic elevator control switch, as the case may be, the retractable cam **Y** is automatically released, which acting through the roller **17** in contact therewith, swings the arm **15**. This rotates the shaft **11** and the cam **18** thereon, lifting the yoke **19**, the lever **21** and the catch **7** and releasing the latch **23** so that the door may be opened.

Opening the door withdraws the bus bar **31** and opens the operating circuit so that the elevator cage cannot be moved until the door is again closed. The positive engagement of the sliding plate catch **7** with the latch **23**, is proof against tampering. Some forms of pivoted spring actuated bell-crank catches can be jarred out of engagements by violently shaking the door. This danger is eliminated by the present invention.

The make and break switch **28—31** is insulated by sheets of dielectric material, such as **33**, interposed between the contact members and the adjacent covers **2, 3** in accordance with the prevailing Underwriters' Code.

Having fully described this invention and its mode of operation, what is claimed and desired to secure by Letters Patent is:

1. A door lock comprising an enclosing case; a shaft protruding from said case and having a cam thereon within said case; a catch slideable in said case and having a latch opening therethrough, a pressure lever pivoted within said case, engaging said catch and actuated by said cam and normally holding said catch in locking position; and a latch having an inclined nose engaging said latch opening and lifting said catch against the resistance of said lever.

2. A door lock comprising an enclosing case; a shaft protruding from said case and having a cam thereon within said case, said cam having lugs extending on opposite sides of said shaft below the axis thereof; a catch slideable in said case and having a latch opening therethrough; a pressure lever pivoted within said case, engaging said catch and actuated by said cam and normally holding said catch in locking position; and a latch having an inclined nose engaging said latch opening and lifting said catch against the resistance of said lever.

3. A door lock comprising an enclosing case; a shaft protruding from said case and having a cam thereon within said case, said cam having lugs extending on opposite sides of said shaft below the axis thereof; a catch slideable in said case; a pressure lever pivoted in said case and normally holding said catch in locking position; a yoke straddling said shaft, actuated by said cam lugs and engaging said lever to slide said catch when said shaft is rotated; and a latch adapted to open and engage said catch.

4. A door lock comprising an enclosing case having an internal bracket; a block adjustably mounted on said bracket; a shaft rotatable in

said block and protruding from said case; a cam on said shaft within said block; a catch slideable in said case; a pressure lever pivoted in said case and engaging said catch; a stem guided in said block between said cam and catch lever and sliding said catch when said shaft is rotated; and a latch adapted to open and engage said catch.

5. A door lock comprising an enclosing case with a shaft opening through one of its lateral walls; reversible side plates on the opposite sides of said case, one of said plates having a shaft hole therethrough; a block within said case and adjustable relative to said shaft hole; a shaft rotatable in said block and protruding through said hole selectively; a catch slideable in said case; a pressure lever pivoted in said case, engaging said catch and actuated by said shaft; and a latch adapted to slide into and engage said catch.

6. A door lock comprising an enclosing case, a block adjustably mounted in said case; a shaft pivoted in said block and protruding from said case and having a cam thereon within said block; a stem guided in said block and actuated by said cam; a pressure lever pivoted in said case and actuated by said stem; a catch slideably guided in said case and actuated by said lever and having an opening therethrough; and a latch adapted to displace said catch and enter the opening therein.

7. A door lock comprising an enclosing case, a block mounted in said case; a shaft pivoted in said block and protruding from said case and having a cam thereon within said block; a stem guided in said block and actuated by said cam; a pressure lever pivoted in said case and actuated by said stem and having a lug thereon; a catch slideably guided in said case and pivotally engaging said lug and having an opening therethrough; and a latch adapted to displace said catch and enter the opening therein.

8. A door lock comprising an enclosing case, a block rotatably adjustable in said case and having a stem guided therein substantially in line with the axis of said block; a shaft pivoted in said block and protruding from said case; a cam on said shaft actuating said stem; a pressure lever pivoted in said case and actuated by said stem; a catch slideably guided in said case and actuated by said lever; and a latch engaging said catch.

9. A door lock comprising an enclosing case mountable on a door frame; a block adjustably mounted in said case; a shaft pivoted in said block and protruding from said case and having a cam thereon within said block; a stem guided in said block and actuated by said cam; a pressure lever pivoted in said case and actuated by said stem; a catch slideably guided in said case and actuated by said lever; a latch on a door movable relative to said frame and engaging said catch; a dielectric base in said case having separated electric contacts thereon; an insulator on said door and projecting into said case and having a bus bar thereon and contacting one of said contacts on said base; and a yielding blade on an insulator on said catch in said case and contacting said bus bar and the other of said contacts and closing an electric circuit when said door is closed and latched.

10. A door lock comprising an enclosing case mountable on a door frame; a pressure lever pivoted in said case; a catch slideably guided in said case and actuated by said lever and having an insulator projecting therefrom; a shaft pivoted in and protruding from said case and actuating said lever; a latch mounted on a door movable relative to said frame and engaging said catch;

a base block in said case having separated electric contacts thereon; a wiping blade mounted upon said base block and resting against one of said contacts; a yielding blade mounted on said insulator on the catch; an insulating block on said door and having a bus bar thereon projecting through an opening in said case and having make-and-break contact with said wiping blade and yielding blade respectively, when said door closes or opens.
